[57] ABSTRACT

In a track surfacing machine, a vibratory surface tamper is mounted on a vertically adjustable carrier on the machine frame, and a generally planar resilient plate for damping the vibrations of the surface tamper is mounted between the tamper and the carrier.

MOBILE TRACK SURFACING MACHINE

The present invention relates to improvements in mobile track surfacing machines, such as track tampers and/or track leveling or lining machines.

It has been proposed to mount on the frame of such machines a vibratory surface tamping body, the vertical adjustment of a carrier for this body placing a tamping face of the tamping body in tamping contact with the surface of the track ballast laterally adjacent the track and/or in a crib. Vibrating means is operatively associated with, and preferably mounted in, the surface tamping body for vibrating the body.

It is the primary object of this invention to protect the machine frame in a simple and effective manner from the vibrations of the surface tamper and simultaneously to increase the efficiency of the tamper by keeping at least a substantial portion of the vibratory power in the surface tamper instead of it being transmitted to the frame where it is, of course, lost.

Through the achievement of this object, it is possible to operate the vibratory surface tamper at its maximum vibratory power without endangering the mounting parts of the surface tamper and thus to shorten their useful life.

The above and other objects are accomplished in accordance with the invention with means for damping the vibrations of the surface tamping body mounted between the tamping body and the carrier.

Since such positioning of the damping means may be limited to a relatively small region, the damping means may be relatively small and compact. Suitable design of the damping means will also make it possible for the tamping face of the surface tamper to make firm contact with the surface of the ballast so that the tamper will operate at highest efficiency.

According to a preferred feature of the present invention, the surface tamping body has a generally planar tamping face and the damping means is a generally planar resilient element extending in a plane substantially parallel to, or forming an acute angle with, the tamping face. This planar configuration of the damping means produces an advantageously even distribution of the tamping forces over a relatively large area of ballast but also assures a firm contact between the tamping face of the surface tamper and the ballast, even where the latter has a rather uneven surface.

The above and other objects, advantages and features of this invention will become more apparent in the following detailed description of certain now preferred embodiments thereof, taken in conjunction with the accompanying drawing wherein

FIG. 1 is a schematic side view of a combined track leveling and lining machine of generally conventional construction,

FIG. 2 is a perspective view of the mounting of a surface tamper on the machine frame according to the invention,

FIG. 3 is a side view, partly in section, of another embodiment of the mounting surface tamper, and

FIG. 4 illustrates a modification of the damping means illustrated in FIG. 3.

Referring now to the drawing and first to FIG. 1, there is shown the elongated frame 1 of a combined track leveling and lining machine running on track 3 on wheels 2, the track ties 4 resting on ballast bed 8.

An overhanging portion of the machine frame carries the track lifting apparatus 5 and the tie tamping means 6 for fixing the leveled track in position after it has been graded by apparatus 5. A track lining apparatus 7 is mounted between the front and rear wheels to move the track laterally. In addition to the tamping means 6, which tamp the ballast underneath the ties, the machine frame also carries an elongated surface tamper 9 for tamping the ballast laterally adjacent the track in the general region of the track lining apparatus so that the ballast may be tamped on the side of the track from which it has been laterally moved during lining. As indicated in broken lines, a similar surface tamper 9' may also be carried on the frame in the region of the track lifting apparatus 5. A carrier 10 is mounted on frame 1 for vertical adjustment so as to place a tamping face of the tamping body 9 in tamping contact with

the surface of the track ballast. The illustrated machine also includes another surface tamper 11 for tamping the cribs, this tamper being mounted on carrier 13 which is vertically adjustable by pressure fluid drive 12. The surface tampers are vibratory.

All of the above-described structure is generally conventional, and the vibratory surface tampers mounted according to the present invention will now be described in connection with some preferred embodiments.

Referring first to FIG. 2, there is shown a carrier arm 14 mounted on machine frame 1 for vertical adjustment, as indicated by the double-headed arrow, for instance by being pivoted to the frame, only the outer end of the carrier being shown. To make the distance of the surface tamper carried by arm 14 adjustable in relation to the machine frame, the surface tamping body is mounted on the carrier 14 by means of a bearing 15, the carrier 14 being glidably journaled in the bearing and fixed thereto at selected distances from the machine frame. Threaded bolts, screws or the like 15' affix mounting plate 16 to the carrier 14.

The hollow surface tamping body comprises a channel-shaped upper part 23 and a lower channel-shaped part 22, the lower part being telescoped into the upper part and being affixed, for instance by welding, to a U-shaped member 21 whose horizontally extending web moves in a cut-out in the upper part 23. A vibrating means constituted in the illustrated embodiment by a cam shaft 24 is operatively associated with the surface tamping body, extending through its hollow interior, to vibrate the body, parts 22 and 23 forming a housing for the cam shaft.

According to the invention, a vibration damping means is mounted between the tamping body and the carrier 14, the damping means shown in FIG. 2 being interposed between mounting plate 16 and a parallel mounting plate constituted by the horizontal web of U-shaped member 21. The illustrated damping means is a generally planar resilient element constituted by a solid plate 17 of rubber or like elastic material. The surface tamper part 22 has a generally planar tamping face 22a and the rubber plate 17 extends in a plane substantially parallel to the plane of the tamping face. As shown, the damping plate is spaced from the mounting plates 16, 21, being sandwiched therebetween.

As clearly shown in FIG. 2, the elastic damping plate 17 is attached to the mounting plates 16, 21 at spaced points, the attachment points between the plate 17 and one of the mounting plates being staggered from the attachment points of plate 17 and the other mounting plate. The attachment points extend in parallel rows transversely of the longitudinal extension of the surface tamping body, the rows of attachment points with one mounting plate being staggered from the rows of attachment points with the other mounting plate. A series of elongated convex spacing members 18 are interposed at the attachment points between the damping plate 17 and the mounting plates 16 and 21, the spacing members being parallel to each other and the convex portions of these members contacting the respective mounting plates. A like series of elongated convex anchoring members 19 are interleaved between the spacing members, with pairs of one spacing member and one anchoring member being in register. The spacing member 18 of each pair is interposed between plate 17 and one mounting plate 16 or 21, and the anchoring member 19 of each pair is interposed between the plate 17 and the other mounting plate. Fastening means, such as the illustrated threaded bolts 20 connect each pair of spacing and anchoring members to a respective one of the mounting plates, the bolts passing through the convex anchoring member in contact with the damping plate 17, through the damping plate, and through the convex spacing member in contact with the opposite mounting plate into this plate.

Another embodiment of the damping means is shown in FIG. 3. In this embodiment, the vibratory surface tamper is mounted for tamping the ballast 8 laterally adjacent ties 4 of track 3. The pivotal carrier 14' of the surface tamper is linked

to laterally extending arm 26 which is pivotal in a vertical plane by means of pressure fluid drive 27 whose one end is linked to bracket 29 mounted on machine frame 1 while the other end thereof is linked to the pivotal arm 26. This arm, on the other hand, is linked to the carrier 14' and to bracket 30 on frame 1, respectively, a further pressure fluid drive 28 being linked to the carrier and to bracket 30, respectively, for proper placing of the vibratory surface tamper on the ballast. The tamper includes an elongated part 22' having a tamping face and a mounting plate 21', similarly to the embodiment of FIG. 2. Also similarly to FIG. 2, the carrier has affixed thereto a mounting plate 16'. At least three fastening members, such as bolts 20', are evenly distributed over the plane of the planar rigid elements 16' and connect the mounting plate 21' of the surface tamper to the mounting plate 16' of the carrier.

The damping means in this embodiment consists of highly elastic, yielding damping elements 25 associated with the bolts 20'. In FIG. 3, a pair of frusto-conical sleeves are coaxially mounted on the bolts, being anchored between the carrier 14' and the mounting plate 16', spacing members being interposed between the mounting plate 16' and the mounting plate 21' of the surface tamper, although such damping elements may also be anchored between the tamper part 22' and the mounting plate 21'. As shown in FIG. 3, the frusto-conical yielding sleeves 25 of each pair taper towards each other.

In the modification of FIG. 4, only a single frusto-conical yielding sleeve is anchored between the mounting plate 16' and the carrier 14'. In both modifications of this embodiment of the tamping means, the even distribution of at least three attachment points is important to increase the efficiency of the surface tamper and to avoid transmission of the vibrations to the machine frame.

While certain preferred embodiments have been described and illustrated, many modifications and variations may occur to those skilled in this art, particularly after benefiting from the present teaching, without departing from the spirit and scope of the present invention as defined in the appended claims.

What we claim is:

1. A mobile track surfacing machine comprising
  1. a frame,
  2. a carrier mounted for vertical adjustment on the frame,
  3. a vibratory surface tamping body having a generally planar tamping face mounted on the carrier,
    - a. vertical adjustment of the carrier placing the tamping face of the tamping body in tamping contact with the surface of the track ballast,
  4. a vibrating means operatively associated with the surface tamping body for vibrating the body, and
  5. a generally planar resilient means for damping the vibrations of the surface tamping body,
    - a. the resilient means being mounted between the tamping body and the carrier, and being attached thereto at a multiplicity of attachment points substantially evenly distributed over the area of the resilient damping means.
2. The mobile track surfacing machine of claim 1, wherein the carrier extends laterally from the frame for placing the surface tamping body in contact with the ballast laterally adjacent the track, and the resilient damping means extends in a plane forming an acute angle with the plane of the tamping face.
3. The mobile track surfacing machine of claim 1, wherein the vibration damping means includes a solid plate of elastic material.
4. The mobile track surfacing machine of claim 3, further comprising a pair of mounting plates for the solid elastic damping plate, one of the mounting plates being affixed to the carrier and the other mounting plate being affixed to the sur-

face tamping body, and the elastic damping plate being sandwiched between, spaced from, and attached to, the mounting plates.

5. The mobile track surfacing machine of claim 1, wherein the damping means comprises a generally planar rigid element affixed to the carrier, at least three fastening members evenly distributed over the plane of the rigid element for connecting the surface tamping body to the rigid element, and highly elastic, yielding damping elements associated with the fastening members.

6. The mobile track surfacing machine of claim 5, wherein the fastening members are threaded bolts, and the damping elements are frustoconical sleeves coaxially mounted on the bolts.

15 7. The mobile track surfacing machine of claim 1, wherein the resilient damping means extends in a plane substantially parallel to the plane of the tamping face.

8. A mobile track surfacing machine comprising

1. a frame,
2. a carrier mounted for vertical adjustment on the frame,
3. a vibratory surface tamping body having a generally planar tamping face mounted on the carrier,
  - a. vertical adjustment of the carrier placing the tamping face of the tamping body in tamping contact with the surface of the track ballast,
4. a vibrating means operatively associated with the surface tamping body for vibrating the body,
5. a generally planar resilient means for damping the vibrations of the surface tamping body, and
6. a pair of mounting plates for the resilient damping means,
  - a. one of the mounting plates being affixed to the carrier,
  - b. the other mounting plate being affixed to the surface tamping body, and
- c. the resilient damping means being sandwiched between, spaced from, and attached to, the mounting plates at spaced points, the attachment points being substantially evenly distributed over the area of the mounting plates.

9. The mobile track surfacing machine of claim 8, wherein the resilient damping means is a solid plate of elastic material being substantially coextensive with the mounting plates.

40 10. The mobile track surfacing machine of claim 9, wherein the attachment points between the elastic damping plate and one of the mounting plates is staggered from the attachment points of the damping plate and the other mounting plate.

45 11. The mobile track surfacing machine of claim 10, wherein the attachment points extend in parallel rows transversely of the longitudinal extension of the surface tamping body, the rows of attachment points with one mounting plate being staggered from the rows of attachment points with the other mounting plate.

12. The mobile track surfacing machine of claim 11, further comprising a series of elongated convex spacing members between the damping plate and a respective one of the mounting plates arranged in said parallel rows, a like series of elongated convex anchoring members, pairs of one spacing member and one anchoring member being in register, with the spacing member being interposed between the damping plate and one mounting plate and the anchoring member being interposed between the damping plate and the other mounting plate, and means for fastening the spacing member and anchoring member of each pair to a respective one of the mounting plates.

55 13. The mobile track surfacing machine of claim 12, wherein the fastening means are threaded bolts passing through the convex anchoring member in contact with the damping plate, through the damping plate, and through the convex spacing member in contact with the opposite mounting plate into said mounting plate.
